Primary Examiner—Lisa P. Lichtenstein
Attorney, Agent, or Firm—Natan Epstein**[57] CLAIM**

The ornamental design for a three dimensionally shaped synthetic foam sheeting, for use in mattress cushions and seat cushions, as shown and described.

DESCRIPTION

FIG. 1 is a top plan view of a three dimensionally shaped synthetic foam sheeting for use in mattress cushions and seat cushions shown, broken away to indicate indeterminate length, showing our new design;

FIG. 2 is an enlarged fragmentary top side perspective view thereof taken in the area designated by the numeral 2 in FIG. 1;

FIG. 3 is a side elevational view FIG. 2;

FIG. 4 is a top plan view of FIG. 2; and,

FIG. 5 is a bottom plan view of FIG. 2.
